UNITED STATES PATENT OFFICE.

JOHANN HEGEDÜS, OF NEW YORK, N. Y.

EXTENSION-TABLE.

SPECIFICATION forming part of Letters Patent No. 304,929, dated September 9, 1884.

Application filed February 21, 1884. (No model.)

To all whom it may concern:

Be it known that I, JOHANN HEGEDÜS, a citizen of Austria-Hungary, residing at New York, in the county and State of New York, 5 have invented new and useful Improvements in Extension-Tables, of which the following is a specification.

This invention relates to a table provided with two leaves, either or both of which can 10 be pushed beneath the table-top or drawn out and secured in a position level with said top.

The peculiar and novel construction of my 15 table is pointed out in the following specification and illustrated in the accompanying drawings, in which—

Figure 1 represents an inverted plan when the extension-leaves are pushed in. Fig. 2 is a vertical section of the same in the plane $x-x$, Fig. 1. Fig. 3 is an inverted plan when 20 the extension-leaves are drawn out. Fig. 4 is a vertical section of the same in the plane $y-y$, Fig. 3.

Similar letters indicate corresponding parts.

In the drawings, the letter A designates the 25 frame, which is supported by the legs B, and which is provided with a central slat, C, which is secured on the end pieces of the frame and extends beyond the same, and serves to support the table-top D, said top being firmly 30 secured to this slat by screws $a-a$ or by other suitable means. By the slat C the top D is raised above the frame A, so as to leave spaces on each side of the slat for the extension-leaves E E'. These leaves are provided at 35 their inner edges with tongues $b-b'$, which, when the leaves are pushed in, engage with grooves $c-c'$ in the opposite edges of the slat C, and when the leaves are drawn out said tongues engage with grooves $d-d'$ in the edges 40 of the top D. Each of the leaves E E' is supported by two slides, $e-e$, $e'-e'$, respectively, and the slides $e-e$ fit into guide-grooves f in the side bar g of the frame A, while the slides $e'-e'$ fit into guide-grooves f' in the side 45 bar g' . With the side bars, $g-g'$, and the central slat, C, are combined braces $h-h'$, and these braces are so situated that they form additional guides for the slides $e-e$ and $e'-e'$, respectively, and that the operation of mov-

ing the leaves E E' in or out can be performed 50 with ease, and the danger that the guides may become jammed in their guide-slots is avoided. Each of the guides $e-e$, $e'-e'$ is provided with a shoulder, i or i' , and if the leaf E is drawn out the shoulders i of the guides $e-e$ bear against 55 springs $j-j$, while, when the leaf E' is drawn out, the shoulders of the guides $e'-e'$ bear against springs $j'-j'$. These springs are secured to the side bars, $g-g'$, respectively, and their object is to retain the tongues $b-b'$ of the leaves E E' 60 in gear with the grooves $d-d'$ in the opposite edges of the table-top D, as shown in Fig. 4. When it is desired to push in one of the leaves, said leaf must be drawn out against the action of the springs $j-j$ or $j'-j'$ until the tongues b or 65 b' clear the groove d or d' . Then the leaf can be depressed and pushed in beneath the table-top D. When the leaves E E' are drawn out, they are sustained against a downward pressure by stops $k-k'$, which swing on pivots $l-l'$, 70 so that they can be turned into their working position, as shown in Figs. 1 and 2.

What I claim as new, and desire to secure by Letters Patent, is—

1. The combination of the frame A, having 75 the side bar g , provided with guide-grooves, the table-top D, having the groove $d-d'$, the central slat, C, interposed between the frame and top and having the groove $c-c'$, the slides e , and the extension-leaf E, having the tongue or 80 tongues b on its inner edge, substantially as described.

2. The combination of the frame A, having the side bar g , provided with guide-grooves, the table-top D, having the groove $d-d'$, the central slat, C, interposed between the frame and top and having the groove $c-c'$, the slides e , the extension-leaf E, having the tongue or 85 tongues b on its inner edge, the stops K , and the springs j , substantially as described. 90

3. The combination of the frame A, having the side bar g , provided with guide-grooves, the table-top D, having the groove $d-d'$, the central slat, C, interposed between the frame and top and having the groove $c-c'$, the braces $h-h'$, 95 the slides e , the extension-leaf E, having the tongue or tongues b on its inner edge, and the stops k , substantially as described.

4. The combination of the frame A, having the side bar *g*, provided with guide-grooves, the table-top D, having the groove *dd'*, the central slat, C, interposed between the frame and top and having the groove *cc'*, the slides *e*, the stops *k*, and the extension-leaf E, having the tongue or tongues *b* on its inner edge, substantially as described.

In testimony whereof I have hereunto set my hand and seal in the presence of two subscribing witnesses.

JOHANN HEGEDÜS. [L. S.]
